UNITED STATES PATENT OFFICE.

ALLIE S. FREED, OF NEW YORK, N. Y.

DESIGN FOR A TEXTILE TRIMMING.

51,107.

Specification for Design.

Patented Aug. 7, 1917.

Application filed May 3, 1917. Serial No. 166,272. Term of patent 3½ years.

To all whom it may concern:

Be it known that I, ALLIE SAMUEL FREED, a citizen of the United States, residing in the city of New York, borough of Manhattan, in the county and State of New York, have invented a new, original, and ornamental Design for a Textile Trimming, of which the following is a specification, reference being had to the accompanying drawing, forming a part thereof.

The figure is a plan view of a textile trimming showing my new design.

I claim:

The ornamental design for a textile trimming as shown.

ALLIE S. FREED.
